CAN PERFORATING DEVICE

Jay Earl Anderson, Dallas, Tex.

Application April 25, 1949, Serial No. 89,378

4 Claims. (Cl. 30—6.1)

2

This invention relates to devices for opening cans and it has particular reference to a device adapted to perforate a can to provide a pouring as well as a vent opening.

The principal object of the invention is to provide a can perforating device consisting of a base to support a can to be perforated, a pivoted upright, a perforating arm and an actuating lever so pivotally related and spring controlled as to permit displacement of the pivoted elements to inoperative position so that the latter will offer no obstruction to the cans as they are placed on and removed from the base. Moreover, by virtue of the compound leverage afforded by the peculiar relationship of parts, perforating operations may be accomplished with greater speed and less effort since the parts are at all times in readiness to function with but minimum displacement of the operating handle.

Another object of the invention is to provide a can perforating device in which the blades are designed to turn under the metal at the edges of the apertures which is desirable in opening cans of fruit juices, beer and other beverage consumed directly from the can.

With the foregoing objects in view, the invention has further reference to certain features of accomplishment which will become apparent as the description proceeds, taken in connection with the accompanying drawings wherein:

Figure 1 is a perspective view of a can perforating device constructed according to the present invention.

Figure 2 is a side elevational view showing in solid and dotted lines the operative and inoperative positions respectively of the parts, and

Figure 3 is a plan view of a perforated can top.

Continuing with a more detailed description of the drawing, reference numeral 10 denotes a base of any desired shape, having holes 11 therein to receive screws for securing the same stationarily to a suitable support. Affixed to the base as by screws 12 is a stationary upright 13, serving as a stop for a can 14 in perforating position on the base and prevents overturning of the can during the perforating operation. Performing a like function is an arcuate flange 15 cast integral with the base.

A boss 16 is also formed on the base behind the upright 13 and is apertured to receive a pin 17 which serves to secure pivotally to the boss a standard 18. A protuberance 19, formed on the lower end of the standard provides a stop to limit rearward pivotal displacement of this ele-

ment as suggested by the dotted lines in Figure 2.

Pivoted at 20 intermediate its ends to a point spaced below the upper end of the standard 18 is an arm 21. This arm, herein referred to as the perforating arm, is equipped with can perforating blades consisting of a steel strap 22, affixed longitudinally to the arm 21 by screws 23 and whose ends are each pointed to define cutting blades 24 and 25. The blade 24 is slightly shorter than the companion blade 25 and serves to provide a vent opening 26 (Fig. 3) while the blade 25 punches the pouring opening 27.

An operating lever 28 is pivoted at 29 to the upper end of the standard 13 and its rear end extends rearwardly to receive a pin 30 by which an end of a link 31 is pivoted to the lever. The opposite end of this link is pivoted at 32 to the rear end of the perforating arm 21.

The rear end of lever 28 has a short, apertured extension 33 to which is attached an end of a coil spring 34 which is brought under tension when the operating lever is depressed and thus tends to hold the lever in raised or inoperative position. Since the lever 28, arm 21 and link 31 are pivoted together, the spring 34 retains these elements in the retracted position shown in dotted lines in Figure 2 so that they will not interfere with the placing of a can on the base 10 or its removal therefrom, yet will dispose the operating lever in a position readily accessible for a forward and downward thrust effective to bring the arm 21 and its blades into puncturing relationship with the top of the can 14.

The pivoted standard 18 is unaffected by the coil spring 34 but is held normally in a rearwardly tilted position, which is likewise exemplified in dotted lines in Figure 2, by means of a light coil spring 35, one end of which is enclosed in a housing defined by a boss 36 formed on the standard 18. The free end of the spring 35 bears against the rear face of the upright 13 and thus forces the standard outwardly from the upright and is collapsed when the operating lever is depressed. The spring 35 is necessarily light so that its resistance may be easily overcome when the lever 28 is operated so that the cutters 24 and 25 may be brought far enough forward that the holes made thereby will be of uniform size after each operation.

It is obvious from the foregoing that the form and relationship of parts is such that the operating lever 28 is always in an advantageous position for ready manipulation while at the same time there is nothing to obstruct placement and

removal of the can. Also, the compound lever-
age afforded enables the perforating arm 21 to
be brought into near parallelism with the plane
of the can top to effect almost simultaneous en-
gagement of the puncturing blades 24 and 25
with the top of the can.

Manifestly, the construction as shown and de-
scribed is capable of some modification and such
modification as may be construed to fall within
the scope and meaning of the appended claims 10
is also considered to be within the spirit and in-
tent of the invention.

What is claimed is:

1. A can perforating device including a base,
a standard pivoted to the base and capable of 15
limited rocking displacement, a blade carrying
arm pivoted at its midsection to said standard;
an operating lever pivoted to said standard above
the pivot of said arm, a link pivotally connecting
the rear ends of said arm and lever, a spring for 20
holding said arm and lever in retracted position
and spring means resisting forward movement
of said standard when said lever is actuated to
dispose said perforating arm in inoperative re-
lation to a can supported on said base. 25

2. A can perforating device comprising a base,
an upright pivoted on said base, an operating 30
lever pivoted intermediate its ends to the upper
end of said upright, a link pivoted at one end to
the rear end of said operating lever, a perforat-
ing arm pivotally connected intermediate its ends
to said upright below the upper end of the latter,
and having pivotal connection at its rear 35
end to the opposite end of said link whereby to be
actuated by said lever, a pair of spaced apart
perforating blades carried by said perforating
arm, spring means effective to resist forward and
downward displacement of said lever in the op- 40
erative movement of said perforating arm and
means normally resisting forward pivotal dis-
placement of said standard.

3. A can perforator comprising a base and a

standard pivoted at its lower end to said base
for limited rocking displacement thereon, an arm
pivoted between its ends to said standard below
the upper end of the latter, a pair of perforat-
ing blades mounted on the forward end of said
arm, an operating lever having pivotal connec-
tion with the upper end of said standard, a link
pivotally connected between the rear ends of said
arm and operating lever, the latter adapted to
be forwardly and downwardly displaced to dis-
pose said arm and blades in perforating relation-
ship with the top of a can on said base.

4. A can perforated including a base, a stand-
ard pivoted to the base for limited rocking dis-
placement, a can support having an upright por-
tion adjacent said standard, a hollow boss on
said standard at its midsection, a coil spring in
said boss adapted to bear against the upright
portion of said can support to resist forward dis-
placement of said standard, a bladed arm pivoted
intermediate its ends to said standard below
the top of the latter, a lever also pivoted
intermediate its ends to said standard at the
top of the latter, a link having pivotal relation-
ship with the rear ends of said arm and lever
for actuating the arm when said lever is
operated and spring means connected between
the rear end of said arm and said standard and
its lower end to hold said lever, arm and standard
in inoperative position. 30
